UNITED STATES PATENT OFFICE.

WILLIAM F. BOSSERT, OF UTICA, NEW YORK.

SEMAPHORE.

1,390,082.

Specification of Letters Patent.

Patented Sept. 6, 1921.

Application filed June 1, 1921. Serial No. 474,187.

To all whom it may concern:

Be it known that I, WILLIAM F. BOSSERT, a citizen of the United States, residing at Utica, in the county of Oneida and State of New York, have invented certain new and useful Improvements in Semaphores, of which the following is a specification, reference being had therein to the accompanying drawings.

10 This invention relates to semaphores and has for an object to provide means for attaching the blade to a spectacle embodying new and improved features of rigidity, economy and reliability.

15 It is well known that in signaling practice the semaphores comprise ordinarily a part known as a spectacle and a part known as the blade, which must be and are attached together in some way, as by means of bolts, rivets or the like. The semaphore, subject as it is to a great number of oscillations, tends to wear the parts connecting the blade with the spectacle, resulting in loose joints, as for instance by the wearing out of the 25 holes, or the wearing smaller of the rivets whereby a looseness is occasioned between the blade and the spectacle resulting eventually in shearing the rivets or bolts or disconnecting the blade from the spectacle to 30 the disadvantage and danger to the signaling system.

The present invention comprises a clamp, which, while employing bolts, does not depend upon the bolts for the connecting of 35 the blade with the spectacle, but provides a clamping mechanism between which and the spectacle the blade is rigidly clamped and held against movement of any kind.

It is well known that the spectacle part 40 of railway signaling semaphores have now been standardized, there being, however, two standards known in the art as the old standard and the new standard, which vary principally in the relation of the bolt holes 45 through the spectacle. An object of the present invention is to provide a single clamping apparatus which will operate in conjunction with both standards, whereby a single uniform clamping apparatus will 50 serve the purpose of clamping blades to all spectacles now commonly in use in railway signaling.

In the drawings:

Figure 1 is a view in side elevation of a 55 conventional standardized spectacle with a

fragment of a blade secured thereto by the improved clamp which forms the subject matter of this application;

Fig. 2 is a view in section taken on line 2-2 of Fig. 1;

Fig. 3 is a view in plan of the clamping unit with the bolts and wedge members removed;

Fig. 4 is a view in inverted plan of the wedge member with the bolt shown in section;

Fig. 5 is a view in plan of a modification wherein two of the clamping members are connected by bridge pieces;

Fig. 6 is a view in section of a modified 70 type of clamping member and wedge members, and

Fig. 7 is a view in elevation of the clamping member used in the modification shown at Fig. 6.

Like characters of reference indicate corresponding parts through the several views.

At Fig. 1 a standard spectacle is shown as an entirety at 10, such spectacle embodying features combined with the present invention consisting of flanges 11 and 12 and an auxiliary flange 13.

Except for minor details of design and for the difference of the spacing of the bolt holes, all of the spectacles in common use in 85 up-to-date railroad signaling conform to the spectacle thus disclosed.

With this spectacle a blade 14 is employed and while the spectacles are stand- 90 ardized there are a considerable number of different blades on the market and in use

for use with such spectacle, and a consider- 95 able number of different means for attaching blades to the spectacles. The specific blade which is shown in the drawing is im-

material to the present invention, which is directed to the clamp, except that the corrugations appearing therein must of neces- 100 sity conform to the curvature of the clamp- ing mechanism which operates therewith.

As shown in the drawing, that portion of 105 the blade 14 which connects directly to the spectacle is provided with corrugations 15 and 16. These corrugations 15 and 16 which

occur at the place designed for attachment to the spectacle are extended preferably throughout the length of the blade for the purpose of stiffening and rigidifying the blade for the purpose of resisting wind pres- 110 sure and other force applied thereto.

As shown at Fig. 1, two of the clamping mechanisms are employed, each comprising a keeper indicated as an entirety at 17, having slots 18 of such dimension as to register with the holes ordinarily found in the spectacle of either of the standards above referred to as the old standard and the new standard. One of these slots is at each end of the member 17 and a wedge member, indicated as an entirety at 19 is employed at the end of the member 17. The keeper is provided with inclined surfaces 20 and 21, the latter being adjacent the opening 18, and the wedge member 19 is provided with co-acting and complementary inclined surfaces 22 and 23, co-acting with the surfaces 20 and 21 respectively under the stress of the bolt 24 which is pivoted thereto at 25 and after extending through the member 17 the blade 14 and the spectacle 10, is provided with a nut 26 and preferably with a locking washer 27.

The wedge member 19, in addition to having a wedging action indicated by the co-action of the surfaces 20 and 22, 21 and 23, is provided with a down-turned finger 28 which engages exteriorly of the flanges 11 and 12, or the flange 13, according to the position of the parts.

As the blades ordinarily employed in semaphore signaling are enameled, it is desirable to protect the enameling against chipping or other damage, for which reason cushions or paddings 29 are interposed between the blade and the spectacle and padding 30 between the clamping member 17 and the blade.

It is obvious that by applying tension by use of the nut 26 upon the bolt 24 the clamping member 19 will be drawn against the member 17 to in turn draw the member 17 against the blade and the blade against the spectacle, considering always the interposition of the padding, but in addition, the pivoting of the bolt 24 to the wedge member and the inter-action of the inclined surfaces first mentioned will draw the fingers 28 against the external edges of the spectacle, which is represented by the flanges 11 and 12, so that the device not only clamps the blade against the spectacle, but, by reason of this engagement with the corrugations 15 and 16 and the flanges 11, clamps the blade against angular movement relative to the spectacle structure. Where the entire equipment of a road, for instance, is standardized to one of the standards, it is found desirable to connect one of the two members 17 into a single structure 17', bridged by means of bars 55 31, as shown at Fig. 5.

As a modification of the structure shown at Figs. 1 to 5 inclusive, a keeper 32 may be employed having perforations 33, not intended as elongated slots such as the openings 18, but to register with the openings

in the spectacle and the blade. The member 23 is conformed to engage against the corrugations 15 and 16, the same as in the types heretofore described, and is provided with inclined shoulders 34. Through the perforation 33 and through the blade bolts 35 are extended bolts 37, connected with the wedging members, which latter comprise two units, the unit 36 having an inclined extremity 37 engaging against the inclined shoulder 34, and the unit 38 having an inclined shoulder 39 bearing against an inclined surface 40 of the unit 36. The units 36 and 38 are provided with elongated openings 41 and 42 respectively, through which the bolt 37 extends, the head 43 of the bolt bearing upon the unit 38. The unit 36 is provided with an engaging extremity 44 and the unit 38 with a finger 45. The action of the parts is such that when stress is applied to the unit 38 by means of the bolt and head 43, the inclined surface 39 slides down the surface 40 and serves to draw the unit 38 with the finger 45 against the flange 12 or 11 and forces the extremity 44 against the inside of such flange, so that the flanges 11 and 12 are clamped rigidly between the members 36 and 38, adding to the security provided in the type shown at Figs. 1 to 5 inclusive, augmenting the clamping of the flanges upon the inner surface. The padding 29 and 30 is employed in this type the same as in the type which is shown at Figs. 1 to 5 inclusive.

In either type it will be understood that blades of substantially the usual and ordinary form in general appearance and effect will be employed requiring only the corrugations 15 and 16 which are found necessary for strengthening the blade and to operate in conjunction with spectacles of standard type, so that the equipment disclosed in the present application may be applied directly to the signaling apparatus now in use without modification. By the employment of devices as disclosed, which clamp the blade firmly and rigidly to the spectacle without danger or possibility of loosening parts by wear and by the proper use of locking washers under the nuts 26, all danger of separation of the blade from the spectacle is eliminated.

What I claim to be new is:

1. The combination with a spectacle of usual and ordinary construction, of a semaphore blade having longitudinal corrugations therein, a clamping member conformed to engage the corrugations of the blade, and wedging members co-acting with the clamping member clamping such member into engagement with the blade and exerting stress upon the margins of the spectacle.

2. The combination with a spectacle of usual and ordinary construction, of a semaphore blade, a clamping member comple-

mentary to the transverse conformation of the blade, wedging members having inclined and movable engagement with the clamping member, bolts from the wedging members inserted through the blade and the spectacle, and means carried by the wedging members for engaging the margins of the spectacle.

3. The combination with a spectacle of usual and ordinary construction, of a semaphore blade proportioned for co-action with the spectacle, a clamping member complementary to the transverse conformation of the blade, bolts extending through the clamping member of the blade and the spectacle, clamping the clamping member against the blade and the blade against the spectacle, and wedge members interposed and receiving pressure from the bolts proportioned to exert stress upon the margins of the spectacle.

4. The combination with a spectacle of the usual and ordinary construction, of a semaphore blade proportioned for co-action therewith, a clamping member complementary to the transverse conformation of the blade, bolts extending through the clamping member of the blade and the spectacle, and wedging members bearing upon the clamping member and receiving stress from the bolt and having hooked extremities engaging the margin of the spectacle under the stress exerted by the combined wedging action and force of the bolt.

5. The combination with a spectacle of usual and ordinary standard, of a semaphore blade proportioned for co-action therewith, a clamping member proportioned to extend transversely across the blade and complementary to the conformation thereof, bolts extending through registering openings in the clamping member of the blade and the spectacle, said clamping member being provided adjacent the openings with inclined cam surfaces, a wedge member having inclined surfaces complementary to the cam surfaces of the clamping member and with hooks at their outer extremities engaging over the margins of the spectacle, and bolts extending through the clamping member of the blade and the spectacle and exerting stress upon the wedging member, tending to move the wedging member upon the inclined cam surfaces to draw the hooked extremities into clamping engagement with the margins of the spectacle and to clamp the clamping member rigidly against the blade and the blade against the spectacle.

6. The combination with a standard spectacle, of a blade proportioned for co-action therewith, a clamping member extending transversely across the blade and complementary to the conformation thereof, said clamping member, blade and spectacle being provided with registering perforations and

the clamping member with inclined cam surfaces adjacent the perforations, a wedging organization co-acting with the cam surfaces of the clamping member and adapted to engage the margin of the spectacle and bolts inserted through the registering perforations and exerting tension upon the wedging member to effect such clamping engagement.

7. The combination with a standard spectacle, of a semaphore blade proportioned to co-act therewith, a clamp member extending transversely across the blade and complementary to the conformation thereof, said clamping member, blade and spectacle being provided with registering perforations, and said clamping member being provided with inclined cam surfaces adjacent the perforation, a clamping organization comprising co-acting parts, one of which engages against the inclined surface of the clamping member and the interior of the marginal flange of the spectacle, and the other engages against an inclined surface of the first-mentioned part and provided with means for engaging the exterior of the marginal flange of the spectacle, and a bolt inserted through the registering openings and through the parts of the clamping member to effect such clamping action.

8. The combination with a standard spectacle, of a blade proportioned for co-action therewith, a clamping member extending transversely across the blade and complementary to the conformation thereof, said clamping member, blade and spectacle being provided with registering perforations and the clamping member with inclined cam surfaces adjacent the perforations, a wedging organization comprising two members, one of which bears against the inclined cam surface of the clamping member and is proportioned to bear against the interior of the flange of the blade when moved in engagement with the cam surface of said clamping member, the other wedge member being provided with an inclined cam surface co-acting with an inclined cam surface of the first wedge member and having a hook adapted to engage the exterior of the flange of the blade when moved in relation to the cam surface of the first mentioned wedging member, and a bolt inserted through both of said wedging members, the clamping member, the blade and the spectacle adapted to move both of said wedging members into wedging engagement with the flange and the clamping member in engagement with the blade.

In testimony whereof I hereunto affix my signature in presence of two witnesses.
